DESIGN FOR A CIGARETTE HOLDER

Raymond A. Lemoyne, Rochester, N. H.

Application May 31, 1941, Serial No. 101,251

Term of patent 7 years

To all whom it may concern:

Be it known that I, Raymond A. Lemoyne, a subject of the King of Great Britain, residing at Rochester, in the county of Stratford and State of New Hampshire, have invented a new, original, and ornamental Design for a Cigarette Holder, of which the following is a specification, reference being had to the accompanying drawing, forming part thereof.

I claim:

The ornamental design for a cigarette holder, as shown.

RAYMOND A. LEMOYNE.
